UNITED STATES PATENT OFFICE

JOSEPH B. ROBSON AND JOHN M. WILLIAMS, OF DELAGUA, COLORADO

MILK BOTTLE HOLDER

Application filed October 21, 1930. Serial No. 490,369.

This invention relates to an improved household milk bottle holder, and it has more particular reference to a box-like cabinet having individual compartments for separate 5 milk bottles wherein said compartments are open at the bottom and provided with internal suspension or retaining means to facilitate application and removal of the milk bottle.

10 The purpose of the invention is to provide a simple, economical, and practical bottle holder which expedites insertion and removal of bottles, and which embodies a lock-equipped cover to guard against unauthorized removal of full bottles from the container.

The specific details constituting the novelty of the structure will become more readily apparent from the following description and 20 drawings.

In the drawings:

Figure 1 is a front or outside elevational view of a bottle holder constructed in accordance with the present invention.

25 Figure 2 is a central vertical sectional view through the same.

Figure 3 is an end view thereof.

Figure 4 is a horizontal sectional view through the lower portion of one of the bottle compartments.

In carrying the inventive conception into practice, we provide a box-like casing generally denoted by the numeral 5. This is open at the bottom and also open at the top. 35 At the last named end however, there is a flanged, pivotally mounted cover or lid 6. The free end portion of the lid is formed with an aperture to permit projection of the apertured end of a padlock retaining element 7.

40 This element 7 has its apertured end projecting above the lid when the lid is closed and the aperture is designed to receive the shackle of an ordinary padlock (not shown). The numerals 8 and 9 designate duplicate attaching strips which are fastened securely across the back of the box and have projecting apertured ends to permit bolting or securing of the device to a post or stationary support.

45 On the interior of the box is a vertical cen-

tralized partition plate 10 which defines individual bottle compartments 11 and 12 respectively. The compartment 12 may include a filler or insert 13 to restrict the size thereof so that one compartment (11) may be used to contain a pint bottle and the remaining compartment 12 to contain a half pint bottle.

Provided in the lower end portions of these compartments 11 and 12 are retaining brackets. There the three distinct species of brackets employed. The numeral 14 for example, forms what may be designated as a latch. This is formed from a single length of metal 15 having a U-shaped portion 16 at the bottom riveted or fastened to the adjacent end 55 wall of the box.

The body portion of this strip inclines upwardly and forms a return bend at 17 to produce a depending spring 18 having a curvate terminal 19 forming a sort of a shoe, to have 60 sliding contact with the inner surface of the complementary wall of the back. This latch 14 may yield in a manner to allow insertion 65 of the bottle upwardly through the open bottom of the compartment.

The numerals 20 designate additional types of brackets. Each bracket 20 comprises a strip 21 fastened at the bottom and inclining upwardly and inwardly and having a horizontal seat portion 22 at the top extending 70 outwardly through an opening 23 in the rear wall of the box. The terminal 24 provides a retaining finger and is disposed on the exterior of the box as illustrated in the drawings.

The numeral 25 designates a duplex or double-acting bracket. This is formed from a single length of metal formed upon itself to provide a pair of downwardly converging arms 26 disposed on opposite sides of the partition walls 10 and riveted in place as at 75. The flat horizontal or bight portion 28 forms a seat and has its intermediate portion movable or workable in a guide opening 29 in the partition.

85 This double seat 28 projects partly into the compartment 12 and partly into the compartment 11 so that it serves both compartments as is obvious. All of these brackets present an inclined cam acting surface to the 90 95 100

bead or neck of the bottle as it is pushed upwardly or inwardly through the open bottom of the selected compartment. Obviously, when the bottle is forced upwardly, a pre-determined distance, it forces all of the brackets simultaneously outward to permit passage. Then as it is moved still further, it allows these various latches or brackets to recede or snap back in place, thus providing a 10 three-point rest or seat for the base of the bottle.

In order to remove the bottles from the container, it is necessary to open the top lid 6 and lift the bottles out in an obvious manner.

It is thought that persons skilled in the art to which the invention relates will be able to obtain a clear understanding of the invention after considering the description in connection with the drawings. Therefore, a 20 more lengthy description is regarded as unnecessary. Minor changes in shape, size, and rearrangement of details coming within the field of invention claimed may be resorted to 25 in actual practice if desired.

We claim:

1. In a bottle holder of the class described, an open bottom casing, a closure at the top of said casing, an internal vertical partition 30 plate in said casing dividing it into a pair of distinguishable bottle receiving compartments, said partition plate being provided adjacent its lower end with an aperture, a double-acting supporting bracket comprising a 35 single length of metal bent upon itself into substantial triangular form, the flat horizontal bight portion thereof being located in said aperture so that the opposite end portions project simultaneously into both of said 40 compartments, the converging arm portions being located on opposite sides of the plate with their free ends securely fastened to the bottom of the plate, and additional supporting elements in said compartment to operate 45 concurrently with said first named bracket.

2. In a milk bottle holder of the class described, a cover equipped open bottom casing, a partition in said casing dividing it into individual bottle compartments, a double- 50 acting resilient supporting bracket carried by the lower end portion of said partition, and having a portion projecting into each compartment, each compartment having an opening in one wall thereof, an additional bracket comprising a single length of metal 55 fastened at its lower end to said apertured wall, and having an upwardly inclined portion, a horizontal seat portion, said seat portion projecting outwardly through the aperture in said wall and having an upstanding 60 retaining clip located on the exterior of said apertured wall.

3. In a milk bottle holder of the class described, a cover equipped open bottom casing, 65 a partition in said casing dividing it into

individual bottle compartments, a double-acting resilient supporting bracket carried by the lower end portion of said partition, and having a portion projecting into each compartment, each compartment having an opening in one wall thereof, an additional bracket comprising a single length of metal fastened at its lower end to said apertured wall, and having an upwardly inclined portion, a horizontal seat portion, said seat portion projecting outwardly through the aperture in said wall and having an upstanding retaining clip located on the exterior of said apertured wall, and an additional bracket 70 in each compartment, said additional bracket 75 comprising a latch formed from a single length of metal having a U-shaped part at its lower end fastened to one of the end walls of the casing, having an upwardly inclined intermediate part provided with a return 80 bend defining a depending spring portion, said spring portion terminating in a curvate extremity in slidable contact with its inner surface of a companion wall of the casing, thus providing three distinguishable brackets 85 in each compartment, the upper ends of 90 said brackets being disposed in an even plane to provide a three-point rest for the base of the bottle when the bottle is pushed upwardly through the open bottom of the casing in an 95 obvious manner.

In testimony whereof we affix our signatures.

JOSEPH B. ROBSON.
JOHN M. WILLIAMS.
